CAMPER UNIT FOR PICKUP TRUCKS

Donald D. Coffman, 5921 Holland Road,
Rockville, Md. 20851

Continuation-in-part of abandoned design application Ser.
No 545,186, Jan. 29, 1975. This application July 7, 1975,
Ser. No. 593,499

Term of patent 14 years

Int. Cl. D12—16

U.S. Cl. D12—156

FIG. 1

FIG. 2

FIG. 3

FIG. 1 is a right front perspective view of a camper unit for pickup trucks showing my new design;

FIG. 2 is a right side elevational view thereof, it being understood that the left side is a mirror image of the right side shown herein; and

FIG. 3 is a right rear perspective view thereof.

This is a continuation in part of design application Ser. No. 545,186 filed on Jan. 29, 1975 and now abandoned.

I claim:

The ornamental design for a camper unit for pickup trucks, as shown and described.
